Specification for Design.

Patented Nov. 7, 1911.

Application filed August 3, 1911. Serial No. 642,126½. Term of patent 3½ years.

To all whom it may concern:

Be it known that I, EMILE SINS, a citizen of France, residing at Paris, France, have invented a new, original, and ornamental Design for Textile Fabrics, of which the following is a specification, reference being had to the accompanying drawing, forming a part thereof.

The single figure of the drawing is a plan

view of a portion of a textile fabric illustrating my new design.

I claim:

The ornamental design for a textile fabric, as shown.
